UNITED STATES PATENT OFFICE.

CHARLES L. DEPOLLIER, OF BROOKLYN, NEW YORK.

SECURING DEVICE FOR WRIST-WATCHES.

1,242,152.

Specification of Letters Patent.

Patented Oct. 9, 1917.

Application filed June 9, 1916. Serial No. 102,676.

To all whom it may concern:

Be it known that I, CHARLES L. DEPOLLIER, a citizen of the United States, and residing in the borough of Brooklyn, of the 5 city of New York, county of Kings, in the State of New York, have invented certain new and useful Improvements in Securing Devices for Wrist-Watches, of which the following is a specification, reference being 10 had to the accompanying drawing forming a part hereof.

This invention relates particularly to devices by which straps or ribbons are connected to watches which may be worn either 15 as wrist-watches or in other ways. As the use of such watches increases it is found that there is objection to anything about the watch or its connections which makes it evident that the watch is intended or adapted 20 for use in different ways. With certain classes of trade it is impossible to sell watches which indicate clearly adaptability for such different uses. It is the object of this invention, therefore, to provide a securing or connecting device by means of which 25 a strap or wristlet, or even a metal bracelet or chain can be connected to a watch, through the medium of an eye secured to the watch-case, of such a character that the devices which directly engage the eye of the 30 watch-case shall be concealed from sight, when the watch is in use, shall permit the strap or band to be brought close to the edge of the watch and substantially in the central 35 plane thereof, and shall permit the metal parts which are seen to have an ornamental appearance rather than an appearance of utility. The improved device comprises a bar which is adapted to overlie the eye of 40 the watch-case and to be engaged therewith on its reverse side, centrally of its length, and may be conformed, on the edge next the watch-case, to the curvature of the watch-case, and has in the same plane with the 45 watch-case an eye or bar for engagement with the strap or band. The invention will be more fully explained hereinafter with reference to the accompanying drawing in which it is illustrated and in which,—

50 Figure 1 is a view in perspective of a watch with a wristlet and connecting devices which embody the invention.

Fig. 2 is a front view of the watch with the securing devices, the strap being 55 moved.

Fig. 3 is a front view of the watch with

the securing devices removed to show the eyes on the watch-case.

Figs. 4 and 5 are detail views showing the construction of the securing devices 60 shown at the right hand of Fig. 2.

Figs. 6 and 7 are detail views showing the construction of the securing devices at the left hand in Fig. 2.

The wristlet, which may be of leather, 65 ribbon or other suitable material and of any suitable character, is shown in Fig. 1 as having two parts *d* and *e* connected by an ordinary buckle *f*. Each part is formed at the end next the watch with a loop or eye 70 adapted for engagement with the corresponding connecting device *g* or *h*. The watch *a* is shown as provided with the usual winding and setting crown *b* and as provided also with eyes *c'* and *c''*. The securing 75 devices *g* and *h* are of substantially the same construction and may be identical. The securing device *g* has a broad bar *g'* which may be conformed at its inner edge to the 80 curvature of the watch-case and has, in the same plane with the watch-case, an eye or bar *g''* for engagement by the wrist-strap or other connection. The bar *g'* covers from view the eye *c''* with which the securing device *g* is engaged. Hinged at one end of the broad bar *g'*, and on the under or reverse 85 side of it, in a plane transverse to the plane of the watch, is a bar *g''* which is provided at the free end with a locking device *g''* adapted to engage a stud *g''* on the end of the broad bar *g'*, so that the hinged bar *g''* may be held in fixed parallel relationship with the broad bar *g'*. On the inner face of one or the other of the bars *g'* and *g''* is a stud *g''*, the end of which lies in close proximity to the other of such bars. In the construction shown the stud *g''* is carried by the hinged bar *g''*. When the stud *g''* is engaged with the eye *c* disengagement thereof is prevented by the locking of the two bars *g'* and *g''* by the locking device *g''*, the free end of the stud being closely covered by the opposite bar. The securing device *h* is likewise provided with a broad bar *h'*, a hinged bar *h''*, 90 a locking device *h''*, a stud *h''* on the end of the bar *h'*, and a stud *h''* carried, in the construction shown, by the hinged bar *h''*. The bar *h''* in this instance, instead of being 95 formed integral with the bar *h'*, is a telescoping bar of usual construction, hinged at one end to the bar *h'* or to a short arm *h''*, and at the other end adapted to engage the

100
105
110
115

short arm h^8 . This provides a ready means for engagement and disengagement of a loop or strap or ribbon.

It will be observed that the employment of the securing devices described permits the strap or ribbon to come into close proximity to the watch-case, avoids any gap between the strap or ribbon and the watch-case, completely covers from view the mechanical devices relied upon, and permits the tension of the strap or ribbon to be substantially in the central plane of the watch, while the appearance of the whole is ornamental and pleasing and in no way suggesting of adaptability of the watch for other uses.

I claim as my invention:

1. A securing device for securing a wristlet to a watch having an eye, comprising a broad bar having an eye in the plane of the watch and formed to overlie and conceal the eye of the watch, a stud on the under side of the bar to engage the eye of the watch, and devices on the under or reverse side of the broad bar to prevent the disengagement of said stud from the eye of the watch.

2. A securing device for securing a wristlet to a watch having an eye, comprising a broad bar having an eye in the plane of the

watch and formed to overlie and conceal the eye of the watch, a hinged bar hinged to the broad bar at one end thereof, on the under or reverse side thereof, to swing in a plane transverse to the plane of the watch, a locking device at the free end of the hinged bar to hold said bars in fixed, parallel relationship, and a stud adapted to enter the eye of the watch and carried on the inner face of one of said bars with its free end in close proximity to the other of said bars.

3. A securing device for securing a wristlet to a watch having an eye, comprising a broad bar conformed to the curvature of the watch, a second bar secured to the first in the plane of the watch and adapted for engagement with a wristlet, a third bar hinged to the broad bar at one end thereof, on the under side, a locking device at the free end of the hinged bar to hold it in fixed parallel relationship with the broad bar, and a stud adapted to enter the eye of the watch and carried on the inner face of one of the bars, which are hingedly connected with its free end in close proximity to the other of said bars.

This specification signed this 7th day of June, A. D. 1916.

CHARLES L. DEPOLLIER.

Copies of this patent may be obtained for five cents each, by addressing the "Commissioner of Patents, Washington, D. C."
